(57) **CLAIM**

The ornamental design for a jacket, as shown and described.

DESCRIPTION

FIG. 1 is a perspective view of a jacket showing my new design;

FIG. 2 is a front view thereof;

FIG. 3 is a rear view thereof;

FIG. 4 is a top view thereof; and,

FIG. 5 is a left side view thereof.

The broken line showing of the indicia in the drawings is for illustrative purposes only and forms no part of the claimed design.

1 Claim, 5 Drawing Sheets

FIG.2

FIG. 3

FIG. 5
